UNITED STATES PATENT OFFICE

133,984

DESIGN FOR A REFLECTOR DEVICE

Samuel M. Dover, Oak Park, Ill.

Application January 29, 1942, Serial No. 105,509

Term of patent 7 years

To all whom it may concern:

Be it known that I, Samuel M. Dover, a citizen of the United States of America, residing at Oak Park, in the county of Cook and State of Illinois, have invented a new, original, and ornamental Design for a Reflector Device, of which the following is a specification, reference being had to the accompanying drawing forming a part thereof, in which:

Figure 1 is a perspective view of a reflector device showing my new design; and

Figure 2, a sectional view of the reflector device taken at the line 2 on Fig. 1 and viewed in the direction of the arrow.

I claim:

The ornamental design for a reflector device, as shown.

SAMUEL M. DOVER.
